AUTOMATIC ELECTRIC TRANSFER
FANCY LOOM

Joseph Stuer, Lawrence, Mass.

Application February 4, 1949, Serial No. 74,638

10 Claims. (Cl. 139—232)

1 This invention relates to what are known as automatic shuttle shifting and bobbin transfer looms such as include, besides the frame, a lay which beats up and carries a bunter, which at the proper time, engages a transfer hammer mechanism or assembly pivoted to the frame and having arms at about a right angle to each other, one arm carrying a pivoted contact dog and the other arm having a head in position to engage a full bobbin from a magazine which is fixed to the frame.

As part of such a magazine are bobbin supporting guideways for full bobbins, there being also, at the bottom of the magazine, giveways which direct a full bobbin to a position where it can be engaged by the head of the transfer hammer and forced down into a shuttle in a shuttle box carried by the lay at the end of its race, to replace an almost empty bobbin therein.

There are also hand fed fancy looms in which there are shuttle boxes on each side of the lay, one or both having cells, and which can be moved up or down by well known devices, known collectively as the head motion, so as to bring any one of the cells on either side opposite the race on the lay.

Such looms usually have mechanism for manipulating the harnesses for the warps and also chains to manipulate the shuttle boxes on one or both sides according to the pattern.

There are also automatic bobbin replacing looms in which there is a magazine on one side under which is a single box and on the other side, a shifting shuttle box with a number of cells each cell carrying up and down, as controlled by the color indication mechanism, a certain shuttle which shuttle carries a bobbin wound with a particular color or kind of thread.

My devices are particularly adapted for this type of loom but some or all parts might be used in other types of bobbin replenishing looms. With this type of loom there is a bobbin filling feeler in position at the front or back on either the right or left side which, when it feels that the filling on any particular bobbin is getting nearly exhausted starts the devices for replacing that bobbin by another full bobbin of the same color and kind. These bobbins of different colors and kinds are in stacks in vertical guideways in a stationary magazine. Pivoted to the frame at the bottom of each of these guideways, is what is known as a cradle which can be turned so as to receive a bobbin and again turned to discharge it.

The usual method of moving these cradles is

2 by means of slides, one for each stack of bobbins in a guideway and each having an upper and a lower nose between which moves a finger on what is known as a color indication shaft such as shown in the patent to Ryon, No. 1,030,748, of June 25, 1912, at 36.

In the Ryon device which is in extensive use, there is what is known as a chopper mechanism in which a certain rod is moved up and down and this moves the fingers on the color indication shaft up and down a greater or less distance, depending on the action of the bobbin filling feeler and the chopper mechanism.

I replace all of the so-called chopper mechanism by electric devices and connections operable by a transfer feeler solenoid and I replace the mechanism, which with Ryon is connected with the rock shaft 25 and other devices for setting the transfer hammer dog in position to

be engaged by a bunter on the lay, by electric devices which are somewhat similar as far as the transfer hammer is concerned to those shown in my previous Patent No. 2,418,324 of April 1, 1947.

25 This invention is applied to a well known type of fancy stationary magazine loom having such well known parts as harnesses, reeds, warp controlling means and lay operating devices together with pickers and other known devices and with very slight changes can be converted from or adapted to other types of looms which are known as pick and pick.

30 It comprises an electric bobbin filling feeler which includes a switch in an electric circuit to close a circuit through a first or slide pin solenoid to pull out a slide locking pin of a slide pin switch thereby allowing a magazine slide which, as shown, is spring pulled, to turn a cradle to receive a bobbin from a stack. This slide pin is also interposed in a second dog pin pulling solenoid or transfer electric circuit which at the proper time and under the proper conditions of operation drops a full bobbin from a cradle into giveways and also either sets the dog of the transfer hammer for engagement with a bunter on the lay for transfer or rather it starts the dog to setting position but instead of moving up in front of the bunter, the parts and timing can be so arranged that it may first hit under the bunter or rise just after the lay and bunter start back.

35 Besides the filler feeling circuit, there is such a transfer electric circuit operable by timing mechanism preferably including a make and break switch to close this circuit through a slide

pin at a predetermined time. This timing can be such as to produce a longer period of time between the tipping of the cradle for the dropping of the full bobbin into the giveways and the moment when the transfer hammer head engages such bobbin than can be done with the Ryon or other devices.

By proper coordination and cooperation with the color indication devices, the full bobbin in a cradle under a stack can be transferred on the second pick after filler feeling or, if the color changes, it can be held in its cradle until the fingers of the color indication shaft, or rather a finger, comes back in line with a nose on a slide after a long interval or while another color or thread in another shuttle is being woven.

I can use a slide with a single nose and with returning spring mechanisms associated with a pin as described, and I preferably also use the solenoid and dog pin construction shown in my patent of April 1, 1947, No. 2,418,324, the transfer devices with such color indication shaft and fingers so that the new full bobbin starts out of its cradle at the same time that the dog pivoted on the transfer hammer starts to rise both being controlled by a dog holding pin and a dog spring.

For clearness and convenience, I will call a pick the interval between front centre when the filling is just beaten up and the next beat up. Generally the picker and shuttle move while the lay is travelling between top, back and bottom centre while the drop boxes are moving between bottom, front and top centre.

With my feeler on the front on the magazine side, the feeling is near front centre and this closes a circuit which releases a spring pulled or spring pressed slide to turn a cradle to receive a full bobbin of the kind in the shuttle. This bobbin remains ready, with the dog of the transfer mechanism not in set position, until the next pick which between top, back and bottom centre throws the shuttle to the box side of the loom where between bottom, front and top centre, if the boxes have not shifted, the timing switch is closed and as the slide pin is out and the slide pin switch is closed, the dog pin pulling circuit is closed and the dog starts to rise or to be set.

This motion of the dog is at a time near the end of the first pick or near the beginning of the second pick and turns the color indication shaft and as there is a finger on that shaft opposite to and above the slide for the right cradle to drop the right full bobbin into the giveways, this finger engaging the nose, moves that slide so that it turns its cradle and starts the fresh bobbin down towards the giveways. Preferably however, the timing is such that while the dog may start towards its position or to be set, it will either strike under the bunter or pass it as the bunter is going back, with the result that while the bobbin starts dropping the actual transfer does not take place until the same shuttle has returned to the position under the magazine at approximately bottom centre and has then been carried forward roughly somewhere between eight and eleven o'clock during which interval actual transfer is accomplished.

In the drawings

Fig. 1 is a diagrammatic front elevation of a loom with a stationary magazine on its right hand side and with a multiple cell drop box on the other side, the well known parts of the loom and the location of a timing switch A being indicated.

Fig. 2 is an elevational view as from the inside of a loom with a magazine on the left hand side instead of the right as in Fig. 1, showing diagrammatically the connecting mechanisms for the pin shaft and the color indication shaft together with the transfer mechanism, the lay and bunter.

Fig. 2A is a view of the turning arm at the end of the color indication shaft and of the connecting link to the transfer mechanism.

Fig. 3 is an elevational view as from the inside of the slides and the cradle operating mechanism for each stack of bobbins in a magazine.

Fig. 3A is a diagrammatic view showing the relation of the color indication shaft with its slide operating fingers to the pin shaft as from the left of Fig. 3.

Fig. 4 is an enlarged elevational detail view of certain parts shown in Fig. 2, namely the pin shaft, transfer hammer switch hands and the locking pins for each slide.

Fig. 5 is a front elevational view of the connections of the pin shaft, a hand and a slide locking pin, together with the relation of each slide to a cradle.

Fig. 5A is an elevational view from the right of the bottom part of a slide, showing the position of the pin and slot when the slide is down.

Fig. 6 is a view similar to Fig. 5, with the pin shaft turned to its position when its hand has pulled out a pin, such pin being indicated by No. 2 while No. 1 pin is not pulled out.

Fig. 6A corresponds with Fig. 5A and shows the position of the pin and slot when the slide is lifted.

Fig. 7 is a diagrammatic plan view showing the relation of the end of a pin at its contact end with the contacting face of a member of the hand contact assembly of a transfer hammer switch.

Fig. 8 shows diagrammatically the filling feeler switch circuit.

Fig. 8A shows a feeler of the electric switch type.

Fig. 9 is an enlarged elevational view similar to Fig. 2A, showing that the arm 70 and the link L are fixed to the color indication shaft.

Fig. 10 is a diagrammatic elevational view of the transfer mechanism in its usual position and with the lay and bunter at the front centre position.

Fig. 11 shows the position of the various transfer parts, when the transfer switch and timing switch are both closed, with the hammer arm of the transfer still raised but with the dog controlling mechanism released and having pulled down on the connecting link to allow the dog to be lifted up under the bunter.

Fig. 12 is a view similar to Figs. 10 and 11 showing the positions of the parts at front centre on the second pick or when the lay and its bunter have accomplished transfer.

Fig. 12A is a detail showing a modification of the shape of a dog and of a bunter.

Fig. 13 is a diagram as from the left of Fig. 10, or what is called the front of the loom, showing the connections from the dog pulling solenoid to the dog release pin.

Fig. 14 is a view similar to Fig. 10, of another transfer resetting device.

Fig. 15 is a view similar to Fig. 11 of such other transfer resetting devices with the dog set for transfer.

Fig. 16 is a cross sectional view of a drive shaft 75 with one embodiment of a timing switch.

Fig. 17 is a diagram of the transfer hammer setting or dog release circuit.

Fig. 18 is a diagrammatic plan view of the timing switch contact parts.

In the drawings, for convenient identification, the following letters are used to describe the major parts of the device as units, the details of which are indicated by numbers.

The whole loom which is of the well known Crompton & Knowles type is indicated by K with a shifting shuttle box with cells on one side and a stationary magazine indicated by M on the other side. A single shuttle box or cell is used under the magazine and as shown, at the front on that side is a filling feeler F of the electrically operable type.

Each of the slides which turn a cradle is indicated by S and the operating nose on this slide is indicated by N.

There are spring pressed pins P, each of which cooperates with a slide S and there is a pin shaft O which carries the devices which I will call hands, each shown as forming a hook which cooperates with a pin P when opposite such a pin as part of a latch and as a part of a multiple contact switch indicated by B, whereby at the right time with the right conditions one of the pins P can be pulled out to release a slide S, this action turning a cradle under a stack in a magazine so as to receive a full bobbin.

The whole transfer hammer T, which includes two arms, one of which carries a head and the other carries a dog D pivoted thereto, is pivoted to the frame of the loom in about the usual manner.

The color indication mechanism as a whole is indicated by I and the color indication shaft which is axially slidable thereby is indicated by C.

The color indication or head motion mechanism also moves shaft O axially but it and shaft C are turned by other mechanisms.

There is a link L which is a connecting member between the dog D and the color indication shaft C and A indicates the make and break timing switch which, at the right time, helps to release a dog pin 38 which has held the spring actuated pivoted dog D out of the path of the bunter carried by the lay of the loom.

Preferably this dog D and this bunter are made of such a shape and size and so positioned that in the preferred type of this device they allow a certain dwell for a longer time period than the usual interval when a cradle is tipped to drop a full bobbin to the time when the head of the hammer of the transfer engages that bobbin.

The loom K is of the well known type described and includes a frame 1, a lay U which is movable back and forth on or with a pivot shaft in a well known manner by a crank action from shaft 101. There is a race 114, a shuttle box 115, as well as a picker, picker sticks, harnesses and other well known parts which it is not necessary to describe.

The magazine M is also of a well known type and is shown as being provided with four guideways 9, 9, 9, 9, in each of which bobbins V of a certain material and color such as red, blue, green and white are stacked.

At the bottom of each guideway is a cradle 8 of a well known type which can be turned but which normally holds up its stack of bobbins and must be turned to receive a fresh one. When so turned it receives a fresh bobbin and when it is then turned back to its original position it

spills out that bobbin. Its turning is controlled by a slide S, also of well known construction, except that instead of having two noses such as shown in the patent to Ryon, No. 1,030,748, to be engaged by a finger carried by the color indication shaft, each slide in my device needs only one nose N as the slide is pulled or actuated by a tension spring 11 which tends to lift it into the position for receiving a bobbin. It also has a pin recess 12 which when engaged by a slide locking pin P locks the slide and therefore its cradle in the position where it does not hold a bobbin but allows a bobbin to drop into the give-ways in the usual manner.

15 100 is the bottom shaft which operates the pickers and in many looms revolves once for every two picks in a well known manner. 101 is the top shaft which revolves once for each pick and operates the lay. 90, 92, 93, 94 indicate the cells in the shuttle box 115 controlled by means of a member 52 from the color indication indicated by I in a well known manner while 91 indicates the single shuttle box under the magazine and 200 indicates the give-ways. These parts are all 25 well known in this type of automatic bobbin changing loom.

Each slide locking pin P has an end 14 to engage a recess 12 and another end 15 which projects out into the path of a slidable contact member 13 with which it forms a slide pin switch B. This end 15 is rounded so that it can be slidingly engaged by the contact member 13 of the slide pin switch B and there is also a spring 16 which is always pressing the pin P against the slide S as in Fig. 5.

The result of this construction is that when a pin shaft O, carrying hands H, H, is turned by a solenoid 20 in a feeler circuit in which is a filling feeler F, which includes a switch to close the circuit on indication, a hand H engages collar 21 on a locking pin P, opposite which that particular hand is located, pulls the pin P out from its recess such as 12 allowing the slide spring 11 to lift its slide thereby turning a cradle 8 by means of slot 83 and pin 82 so as to allow the cradle to receive a full bobbin.

In Figs. 5A and 6A the positions of a cradle 8 and its pin 82 with relation to a slot 83 are indicated.

50 55 Filling feeler F is of the well known electric type as shown in Fig. 8A. The feeler F is of a well known type, with a feeler finger and a spring, not shown, so that when its tip 148 engages a yarn mass or bunch on a bobbin when the lay beats up, finger 147 slides forward but if tip 148 slips on a bare bobbin as shown by the dotted lines in Fig. 8A, its end 146 engages a spring contact 140, which is grounded. This engagement completes the feeler circuit through conductor 143 and through the solenoid 20. This pulls on armature 64 and rod 62 which causes the pin shaft O and hand assembly H to turn, as shown in Figs. 5 and 6.

Each hand H and each contact member 13 of the slide pin switch B as well as the fingers 6, 6 on the color indication shaft C move axially with the pin operating shaft O being caused to do so by the bell crank lever, 50 pivoted at 51, which is connected by a flexible member 52 to the color indication mechanism not shown. See Fig. 2.

Member 13 is insulated as at 10 and the pins P are shown as grounded.

As shown in Fig. 7, the faces of contact members 13 of the feeler and slide pin circuit and 75 the outside or free ends of pins P are all so round-

ed that shaft O can be moved axially with members 13 sliding over the pins P. This is made possible by the arm 165 on shaft O and spring 65, Fig. 5; which normally keeps the members 13 in the position shown in Fig. 5, but allows them to yield as shown in Fig. 6 so that while each contact member 13 can make an electric contact with each of the pins 1, 2, 3, and 4, or rather with each pin when it is pulled out by its hand H, they will not jam as spring 65 allows some yielding.

The pin shaft O is turnable and slidable in the fixed bearings 53 and the color indication shaft C is turnable and slidable in fixed bearings 54. Both shafts are turnable in bearings 55 and 56 in a connecting member E and they are both axially movable therewith and thereby when member E is caused so to move by the bell crank lever 50 pivoted at 51 and connected to the head motion by member 52.

The stacks and slides S are arranged in the usual way and each slide pin pole P for each slide is a member of a multiple contact pole selective transfer slide pin switch B. The other member is any one of the combined hand H and contact members 13 carried by pin shaft O.

The arrangement and position of four pins and two of such assemblies, each including a hand and contact member 13 is shown in Figs. 2 and 4. These hand assemblies, including H and 13, are so positioned with reference to the fingers 6, 6, indicated in Fig. 2, and carried by the color indication shaft C that only one finger 6 can be opposite to or in front of a slide S and therefore below its pin P, which serves as a latch for that slide. This arrangement of the color shaft with two fingers to operate four slides is old and well known in the industry.

As shown in Fig. 3A, there are two hand contact switch members B on shaft O and two corresponding fingers 6, 6, on shaft C in each case positioned and slidable in front of two pair of pins P and two corresponding pairs of slides S, S. The arrangement is such that with two pairs of stacks and slides, there are two fingers such as 6 and two hand contact assemblies such as B, the head motion being so arranged that there cannot be more than one contact member B in engagement with a pin P and the same is true of the corresponding fingers 6, 6, with reference to noses N, N. With only two stacks and drop boxes, only one finger 6 and one member B is needed.

The arrangement and setting is such that only one finger and one hand contact member at any time can be opposite a slide and therefore the transfer circuit can be closed only through a slide pin P which has been pulled out and is held out.

Moreover to completely close the transfer electric circuit through a pin P and a member 13 carried by a hand H, together forming the switch B as shown in Figs. 5, 6 and 7, the timing switch A must also be closed and this switch A is so adjusted that it will close only at or near the end of the movement of the drop boxes and of the color indication shaft when both have almost or entirely come to rest.

This is set preferably at about eleven o'clock, meaning between front and top centre and, in any case, to close the transfer circuit when there is no shuttle on the magazine side of the loom.

It is well known that the time interval of the movement of the color indication shaft and its fingers 6 from slide 1 to 2 is the same as from 1 to 4 and even if all four pins are out, the timing switch will not be closed until just before or when

7 finger 6 is over the nose of and in front of the slide and stack for the shuttle with the color which is next to start for the magazine side.

As shown in Figs. 2 and 4, there is a slot 58 in member E which engages a pin 57 in an arm 59 of lever 50. Fixed to pin operating shaft O is an arm 60 with an arm handle 61 slidable through a pull rod 62 from armature 64 of the solenoid 20 in the feeler circuit operable by filling feeler F. When the feeler F indicates near exhaustion, the solenoid 20 and these connections turn shaft O so that any hand 5 on it which is opposite a slide S will pull out a pin P and allow that slide S to be lifted by its spring 11 and turn its cradle 8.

The color indication shaft C is also turnable in the bearing 56 in connecting member E and is axially movable with shaft O as shown by the dotted lines in Fig. 2.

To turn color shaft C, I provide an arm 63 on shaft C connected by a link L to arm 163, Figs. 2, 9, 10, 11 and 12, of the dog carrier 35 of operating assembly G. This assembly, as shown, is part of the transfer mechanism indicated generally by T, which includes a hammer arm 30 with a hammer head 31 to engage a new bobbin in the giveways, the transfer mechanism being pivoted at 32 to the frame of the loom includes another arm 33 to which at 34 a carrier 35 for dog D is pivoted, Figs. 10 to 15. This dog D may be of more than ordinary length and dog carrier 35 has a pin 36 which connects with a dog setting spring 37 which tends to pull down arm 163 and to lift the dog D up into position in front of the bunter 5 on the day. This dog D and bunter 5 may both be of usual length.

Preferably there is a spring pusher 126 carried by arm 163 to engage the back of dog D, as shown in Figs. 10, 11 and 12.

There may be a stop 164 to limit the movement of dog D, if the bunter 5 is located above or level with the dog carrier and dog pivot shaft 34 or the dog's mouth 166 may be deeper as shown in Fig. 12A to keep the dog under control.

The feeler and slide pin switch circuit is shown in Fig. 8, and includes a feeler F which is grounded, with an arm which does the feeling and when exhaustion is indicated, closes the circuit completely through a wire 143 and solenoid 20 which affects its armature 64 and through connecting member 62 moves the hands as shown in Figs. 5 and 6.

W is a shipper switch through which the current from the ground passes, the switch normally being closed. The feeler circuit is closed only long enough to pull out the particular slide pin opposite the particular color which is in the shuttle being felt.

There is a dog pulling pin circuit shown in Fig. 17 including a solenoid 41 with armature 40 and flexible connection 139 to pin 38, solenoid 41 being fed from the source of electricity when switch W is closed but as wires 141 and 142 are interrupted by timing switch A, except at a certain predetermined time in the revolution of a shaft such as 100, the circuit is not closed even if a member 13 is in contact with a pin P.

When one of the four switches B is closed and switch A is also temporarily closed, the solenoid 41 pulls a dog locking pin 38 which releases a dog D as shown in Figs. 9, 10, 11, 12, 13. When released, arm 163 and link L turn the color indicating shaft C so that the finger 6 opposite the particular slide of the particular color indicated, pushes down on a nose N of that slide, thereby

dropping a full bobbin of that color stack into the giveways.

For convenience and brevity in the claims, the loom of the character described is of the type having a stationary magazine with a plurality of guideways on one side, a single shuttle box under it and on the other side a movable drop box with a number of cells.

The circuit shown in Fig. 8 will be called the feeler circuit, and the circuit shown in Fig. 17, as the transfer circuit while the switch indicated by B will be called the multiple pole selective transfer circuit switch.

The timing switch A is attached to some part of the loom, such as the bottom shaft 100 directly or to some other shaft or part by reducing gears so that it will be closed only when the active shuttle is on the box side or off magazine side of the loom or on every other pick between bottom, front and top centre.

As shown in Fig. 16, the timing switch A has an arm 88 carried by a clamping collar 86 on a shaft 100, they being adjustable thereon by bolts 85, 85, and there being a double switch member 87, 89 carried by any part of the frame 84. Thereby the exact timing of closing the dog pulling circuit shown in Fig. 17 can be regulated.

There is a dog pin 38 which is spring pressed by a spring 39 to engage the back 168 of the dog arm 33 of the transfer T in a position so that it normally locks the dog D in the non-setting position.

Through a flexible connection 139 to the armature 40 of a dog pin pulling solenoid 41 in the same circuit with a slide pin switch B and with a timing switch A, when this dog pin 38 is pulled out, the dog setting spring 37 causes the dog D to rise and if, at that time, the lay is going forward between bottom and front centre, the dog D strikes under the bunter 5 and does not get into full setting position, Fig. 11.

To prevent smashes, instead of an adjusting screw, such as shown at 26 in my previous patent, I prefer to use a spring pusher 126 with a head, a shank and a spring 124, Figs. 10, 11, 12, to engage the back of the dog this spring acting to allow the link L to do its work and to allow the resetting of the parts and to do their work with a certain elasticity.

This pusher 126 also yields when dog D strikes under the bunter.

An elastic pad might replace the spring pusher 126 or the dog D might be fixed to the dog carrier member 35 especially if the switch A is so set that the dog is released as the lay is moving back.

When spring 37 moves arm 163 of carrier 35 down to lift dog D, it depresses arm 163, pulls down link L and turns indication shaft C with its fingers 6, 6, from the full line position to the dotted line position shown in Fig. 6, and if a finger 6 is opposite to and above a nose N on a slide S, its cradle is turned and a full bobbin is dumped into the giveways.

The device operates as illustrated in the drawings.

When the feeler F which is at the front of the loom on the magazine side, indicates near exhaustion of a bobbin with a certain color or kind of thread, similar to those in stack No. 2, the feeler solenoid circuit, Fig. 8, is closed through the solenoid 20 which turns pin shaft O and hands H and as there is a hand opposite the No. 2 slide, (Figs. 5 and 6) that hand engages a pin P forming part of a pin switch and pulls

it out of its slide recess 12 in a slide S which is pulled up by its spring 11 and remains up until the nose N pulls it down turning the cradle, thus allowing a full bobbin to drop into the cradle.

- 5 The feeler F, Figs. 8 and 8A, closes the feeler circuit only long enough to pull a locking pin P, thus releasing slide No. 2 and as soon as the lay with the shuttle and nearly exhausted bobbin move back, allowing the feeler to pivot back to its usual position, thus opening the feeler circuit, the spring 65 returns the shaft O, carrying hand H and contact 13 to the position shown in Fig. 5, but that pin P is held in position shown in full lines in Figs. 6 and 7, resting against its slide and being in position where it is engaging contact member 13. If the shaft O, hand H, and contact 13 are not moved axially, the No. 2 pin and contact 13 have closed the switch B of the dog pin circuit but the timing switch A is not closed. If the timing switch A is set at seven o'clock, as the shuttle carrying the nearly exhausted bobbin goes forward on the off magazine side, that switch A is closed completing the circuit with the result that solenoid 41 pulls a dog pin 38 from its position shown in Fig. 10 whereupon spring 37 pulls down on pin 36 causing carrier 35 to pivot on 34 and starts to lift the dog D but the dog hits under the bunter and is not effective until the next pick, Fig. 12.

- 30 Link L however has been pulled down by arm 163, turning shaft C and through a finger 6 and nose N spills out a No. 2 bobbin which therefore has a full pick or perhaps a little more time to drop into and to get settled in the giveways by the time of actual transfer by contact of hammer head 31 with the fresh bobbin.

- If the timing switch is set at ten o'clock, the rising dog may miss the bunter, but as the bunter is going back, the same thing happens and there 40 is no transfer until the next pick.

- In my previous patent of April 1, 1947, on "Lion Transfer Mechanism," No. 2,418,324, I show a dog control member marked C and a shaft 26, by which it and the dog are pivoted to the short 45 arm of the transfer while there is an arm 50 which engages a cam 51 to reset the device as that arm moves back.

- In Figs. 2 and 10 of this application, I show a connecting link R which near one end is fixed 50 to an arm 70 on shaft C and which near its other end is connected to the long transfer hammer arm 30 through the medium of a slot 71 and pin 72, the connections being such that when the dog pin 38 is pulled out thus allowing 55 the dog setting spring 37 to move the spring pusher member 126 against the pivoted dog D, tending to lift it up into setting or engaging position with the bunter 5, this action also through link L turns shaft C so that if one of its fingers 6 is in line with any of the slides S, it will immediately depress that slide and drop the bobbin 60 therein into its cradle, ready for transfer.

- As shown by the dotted lines in Fig. 9, arms 63 and 70 are fixed to shaft C so that when one is 65 down, the other is up.

- The slot 71 in the link R allows the turning of shaft C by the action of link L with no effect on the hammer arm 30 of the transfer but it does cause a bobbin to be dropped or spilled 70 out of the cradle into the giveways.

- When the lay with bunter 5 then first moves back, pusher 126 and spring 124 lift dog D clear of bunter 5 to engaging position with bunter 5 and then when the lay again moves forward to 75 transfer, as shown in Fig. 12, dog D is held in

placed by stop 164 and the parts are moved to the position shown in Fig. 12. This forward movement of the bunter and dog causes pin 12 to pull down link R and arm 70 turning shaft C and thus moving arm 163 up with link L causing bunter 126 to separate from dog D, while the spring pressed dog pin 38 slides along arm 33 until it catches behind its back 168. When the lay U with bunter 5 now moves back away from dog D, the regular transfer returning spring 9 moves the transfer and carrier 35 to their usual position, the dog D dropping by gravity, and being again engaged by the bunter 126 which has come down with the link L to position shown in Fig. 10. Dog pin 38 behind arm 33 relocks the dog in place.

In Figs. 14, 15, I show a simpler arrangement for resetting consisting of a cam member 80 and a resetting pin 81 on the dog control member C in such a position that when the dog goes up to engage the bunter, this pin engages the bottom part of the cam 80 and as the arm 33 carries the member C and the dog forward on transfer, this causes the dog pin 38 to slide along the side face of the short arm 33 until it drops back of it thus being reset.

The dog D and bunter 5 may be so made that when the dog is moved by the dog setting spring 37, it hits under the bunter and is not entirely set until the next pick when transfer is accomplished as explained.

To be sure that no current will pass through the dog pin pulling solenoid 41 except at exactly the right time, I provide a timing switch A which is shown as operable with the bottom shaft with contacts 87, 89, which will engage preferably between 8 and 12 only when there is no shuttle on the magazine side of the loom.

However, if the timing switch A is set to act at ten o'clock or just at or past front center, the dog will start up as the lay and bunter start back so that the interval between the dropping of a full bobbin into the giveways may be less but the result is otherwise the same.

To allow the contact of arm 88 of the timing switch A to be adjusted, the collar 86 can be moved on shaft 100 by bolts 85 and 85 so that it can engage contacts 87 and 89 at the right time and for the right interval.

Bottom shaft 100 and timing switch A revolve every two picks and switch A is set to be closed while the boxes are moving between bottom, front and top center with no shuttle under the magazine.

For convenience, I will call the pins P from left to right 1, 2, 3, 4, and the shuttles carrying the bobbins 1, 2, 3, 4, in accordance with the slides S which are opposite the pins P.

If the feeler indicates near exhaustion in the No. 2 shuttle and bobbin and has closed the feeler circuit so that switch B through hand H has pulled out the No. 2 pin as shown in Figs. 5, 6, and 7, as this happens on the magazine side between bottom, front and top center, and that shuttle has then been picked to the box side between top, back and bottom center, and then comes back, the transfer is complete because the electric transfer switch B is still closed, B engaging P, and if switch A is set for nine o'clock or front center on the box side, that has completed the circuit and the dog pin 38 has been pulled thus turning color shaft C through link L, causing the nose N to move down the slide S and turning cradle 8 to drop the No. 2 bobbin into the giveways to wait for the shuttle to

come back to the magazine side and to move forward to be transferred at front center on the next pick or forward movement of the lay.

If however the color indication has moved the switch B and hand H, away from No. 2, and also shifted the boxes so that No. 3 is opposite the race 114, and if the No. 3 pin has not been pulled out, no transfer will occur because there is no complete circuit until either No. 3 pin is out or the color indication shifts back to No. 2. In other words, if there is no immediate change in the color scheme, the transfer will occur when the No. 2 shuttle comes back from the box side to the magazine side, but if there happens to be a change at that particular time, No. 2 pin will remain out but the dog pin pulling or transfer circuit will not be completely closed even if the timing switch A is closed on every pick or every other pick between bottom, front and top center.

However, if and when the color indication returns the shuttle of No. 2 with its nearly spent bobbin in line with the race, that action also again closes the No. 2 switch B and as the timing switch is set at approximately eight or ten o'clock,

as the boxes move No. 2 shuttle into position, the complete circuit is made through the slide pin assembly switch B and the timing switch A whereby the dog solenoid pulls the dog pin which, through link L, instantly spills out the full No. 2 bobbin from its cradle into the giveways ready for transfer after the shuttle has gone back to the magazine side and the lay with the bunter has moved forward to engage the dog for transfer of the full No. 2 bobbin from the giveways into the shuttle replacing the nearly exhausted bobbin of No. 2.

The length of the various links, connecting members, arms such as 30, 70, 88, 163, pusher 126, the location of pivots, length and location of slots as well as the shape, size and location of dog and bunter can be made, positioned and proportioned according to the particular type or model of loom.

The sequence of operation is that if and when both switches B and A are closed near front centre, the dog lifting spring 37 pulls down on the arm 163 of dog carrier member 35, also on connecting link L, thereby turning color shaft C and moving a finger 6 from the full line position in Fig. 6 to the dotted line position, which action drops the bobbin out of the cradle and turns the cradle from receiving position Figs. 6 and 6A to non-receiving position as shown in Figs. 5 and 5A.

This action also allows the pin P to engage slot 12, Fig. 5, thereby limiting the movement of all of the above parts with the dog in the position shown in Fig. 11 under the bunter or if set at eleven o'clock, it has passed in front of the bunter as the bunter recedes. This condition prevails until the lay with the bunter moves forward pushing back the dog and causing transfer to the position shown in Fig. 12. The feeler is withdrawn during transfer by well known mechanism, not shown, to prevent its feeler finger from being broken.

As the tension of dog spring 37 is still on, the link L alone would not lift the finger 6 into full line position, Fig. 6, and therefore to move these parts back as well as the dog pulling pin 38 to be caught at the back 168 of arm 33, thus locking carrier 35, it is necessary to use the resetting arm R which is pulled down by the downward movement of the arm 30 of the transfer and through arm 70 on shaft C, arm 63 and link L on arm 163 of dog carrier 35 moves all parts back to the position shown in Figs. 2, 10 and 14 with

dog D dropped to non-setting position or to use a device such as shown in Fig. 14 and Fig. 15.

I claim:

1. In a loom of the character described; a plurality of cradle actuating slides each comprising a spring to move a cradle to bobbin receiving position and including a locking recess for a slide locking pin and a cradle discharging nose; an electrically operable bobbin exhaustion filling feeler in a feeler circuit with and to energize a feeler solenoid operable therein; slide locking pins on the magazine, each spring pressed to engage a recess in a cradle slide; the feeler circuit including a multiple pole selective transfer switch having a locking pin as a pole for each slide and means operative by the feeler and solenoid in the feeler circuit to indicate transfer by pulling out a pin; a pin shaft slidable with the color indication shaft from the color indication mechanism and turnable by the solenoid operable from the bobbin exhaustion feeler, said shaft including hands each above a finger on the color indication shaft to disengage each locking pin from a slide locking recess, said hands and the locking pins being contact poles of the multiple pole selective transfer switch which is in a transfer electric circuit including a transfer solenoid; in combination with means between a transfer hammer dog and the color indication shaft to turn the color indication shaft and cause a finger to operate a slide to discharge a bobbin from its cradle in the magazine into the giveways; and a transfer circuit timing switch to open and close the transfer circuit at a predetermined time in a period of two picks through one of the branches of said multiple pole selective transfer switch whereby to turn the color indication shaft to so drop a bobbin and to start the dog setting means in operation.

2. In a magazine loom of the character described having a magazine with a plurality of guideways each for a stack of bobbins and each provided with means to release a bobbin operable by a turnable bobbin release shaft slidable with a turnable and slidable color indication shaft, together with a lay and a bunter carried thereby; an electric filling feeler circuit including a source of electricity, a filling feeler switch, a feeler solenoid and connections to so turn the bobbin release shaft as to release a bobbin from a stack and to set a pole of a transfer circuit switch in a transfer circuit; a transfer assembly comprising a hammer arm, a dog carrier with a dog pivoted thereto, means to move the dog to setting position and dog holding means to hold the dog out of setting position releasable by a dog controlling solenoid in a transfer circuit; means connecting the dog with and to turn the color indication shaft; such transfer circuit including a source of electricity, the dog controlling solenoid to release the dog and to allow it to start for setting position, the transfer circuit switch and a timing switch operable at every second pick to close such transfer circuit through the dog controlling solenoid between bottom, front, and top centre on the off magazine side of the loom on each pick before transfer.

3. In a loom of the character described including a transfer hammer with a spring pressed dog pivoted thereto and locking means for the dog; a feeler circuit including a multiple pole selective transfer circuit switch and a feeler solenoid; a shaft turnable by the feeler solenoid and movable axially with a color indication shaft to move a slide and cause a cradle to re-

ceive a bobbin and to set a pole of the multiple pole selective transfer circuit switch for that slide; a transfer circuit including the multiple pole transfer circuit switch, a transfer solenoid and a timing switch to open and close the transfer circuit at a predetermined time in a period of two picks through one of the poles of the multiple pole transfer circuit switch; the transfer solenoid to release the spring pressed dog of the transfer hammer; and means between the dog and the color indication shaft to turn that shaft to move a slide and cause a cradle to release a bobbin.

4. In a loom of the character described including a transfer hammer with a spring pressed dog carrier member carrying a dog and pivoted to the transfer hammer and locking means for the dog, a feeler circuit including a multiple pole selective transfer circuit switch and a feeler solenoid; a shaft turnable by the feeler solenoid and movable axially with a color indication shaft, to move a slide and cause a cradle to receive a bobbin and to set a pole of the multiple pole selective transfer circuit switch for that slide; a transfer circuit including the multiple pole transfer circuit switch, a transfer solenoid and a timing switch to open and close the transfer circuit at a predetermined time in a period of two picks through one of the poles of the multiple pole selective transfer circuit switch; the transfer solenoid to release the spring pressed dog carrier member of the transfer hammer; and means between the dog carrier member and the color indication shaft to turn that shaft, to move a slide and cause a cradle to release a bobbin.

5. In a loom of the character described including a transfer hammer with a spring pressed dog carrier member carrying a dog and pivoted to the transfer hammer and locking means for the dog, a feeler circuit including a multiple pole selective transfer circuit switch and a feeler solenoid; a shaft turnable by the feeler solenoid and movable axially with a color indication shaft, to move a slide and cause a cradle to receive a bobbin and to set a pole of the multiple pole selective transfer circuit switch for that slide; a transfer circuit including the multiple pole transfer circuit switch, a transfer solenoid and a timing switch to close the transfer circuit at a predetermined time in a period of two picks through one of the poles of the multiple pole selective transfer circuit switch between bottom, front and top center, when there is no shuttle on the magazine side of the loom; the transfer solenoid to release the spring pressed dog carrier member of the transfer hammer; and means between the dog carrier member and the color indication shaft to turn the shaft, to move a slide and cause a cradle to release a bobbin.

6. In a loom of the character described including a transfer hammer with a spring pressed dog carrier member carrying a dog and pivoted to the transfer hammer and locking means for the dog, a feeler circuit including a multiple pole selective transfer circuit switch and a feeler solenoid; a shaft turnable by the feeler solenoid and movable axially with a color indication shaft, to move a slide and cause a cradle to receive a bobbin and to set a pole of the transfer circuit switch for that slide; a transfer circuit including the transfer circuit switch, a transfer solenoid and a timing switch to close the transfer circuit at a predetermined time in a period of two picks through the poles of the transfer circuit switch, when there is no shuttle on the magazine side

of the loom; the transfer solenoid to release the spring pressed dog carrier member of the transfer hammer; and means between the dog carrier member and the color indication shaft to turn that shaft, to move a slide and cause a cradle to release a bobbin.

7. In a loom of the character described, a plurality of spring pressed cradle actuating slides each to operate a cradle for a guideway; means to release and lock each slide, such means forming one slide contact pole of a multiple pole selective transfer switch, such switch including a contact hand to engage each of such slides contact poles and being carried by an operating shaft axially slidable with the color indication shaft and turnable by connections operable by a feeler electric circuit solenoid, interposed in a feeler circuit, when the circuit is closed by a bobbin filling exhaustion feeler, the hand including another contact pole of the transfer switch, one of the contacts of which it sets in such a manner that when one of the slide contact poles is engaged by a hand, it closes one branch of the transfer electric circuit which passes through the transfer switch, a timing switch and through a transfer circuit solenoid which sets in motion means to start the dog towards setting position and means to turn the color indication shaft to operate a slide in such a manner as to drop a bobbin into the giveways; said transfer solenoid and said timing switch operating to close the transfer circuit at a predetermined time in a period of two picks to set in motion means to so operate the color indication shaft and dog only when a slide pole and a contact hand of the transfer switch are engaged.

8. In a bobbin-changing loom having a stationary frame and a movable lay, a bunter carried by the lay on the magazine side to engage the free end of a dog, a magazine holding two or more bobbins and including devices to hold a full bobbin for transfer, a shuttle box carried by the lay to be in position under the full bobbin holding means, bobbin transfer mechanism including a transfer hammer having an arm to engage said full bobbin and a dog holding arm; a dog freely pivoted to the dog holding arm; a dog carrier member carried by and movable with the transfer hammer, said member including means to so move it and the dog as to cause the dog to move to bunter engaging position; a stop to check the dog in bunter engaging position; spring actuated means to hold the dog out of the path of the bunter; a solenoid including an armature and a connection from the armature to the means to hold the dog; said solenoid being in a transfer circuit including a timing switch to close the transfer circuit whereby the dog is released at a predetermined time in a period of two picks between bottom, front and top center when there is no shuttle on the magazine side of the loom.

9. In a bobbin-changing loom having a stationary frame and a movable lay, a bunter carried by the lay on the magazine side to engage the free end of a dog, a magazine holding two or more bobbins and including devices to hold a full bobbin for transfer, a shuttle box carried by the lay to be in position under the full bobbin holding means, bobbin transfer mechanism including a transfer hammer having an arm to engage said full bobbin and a dog holding arm; a dog freely pivoted to the dog holding arm and movable with the transfer hammer; means to so

move the dog as to cause the dog to move to bunter engaging position; a stop to check the dog in bunter engaging position; means to hold the dog out of the path of the bunter; a solenoid including an armature and a connection from the armature to the means to hold the dog serving to release the dog, said solenoid being in a transfer circuit including a timing switch to close the transfer circuit at a predetermined time in a period of two picks between bottom, front and top center when there is no shuttle on the magazine side of the loom.

10. In an automatic shuttle shifting and bobbin transfer loom having a stationary frame, a movable lay carrying a bunter, a transfer hammer pivoted on the frame including a head, a pivoted dog, means to set the dog for transfer, a dog holding pin operable by a transfer solenoid to release the dog and allow it to move to engaging position with the bunter carried by the lay, a bobbin magazine fixed to the frame with a plurality of bobbin supporting guideways, each guideway having a bobbin receiving and discharging cradle at the bottom operable by a slide having a nose, there being giveways from under the cradles to the bobbin transfer position under the bobbin transfer hammer head, a shuttle box on the magazine side, and a shifting shuttle box on the other side with a plurality of cells, a color indication shaft having fingers to engage the noses on the slides, the shaft being turnable to move the selected slide and cause the corresponding cradle to release a bobbin, said shaft being axially slidable by a color indication mechanism, said cradle actuating slides each comprising a spring to move a cradle to bobbin receiving position and including a locking recess for a slide locking pin and the nose; an electrically operable bobbin exhaustion filling feeler in a feeler circuit with and to energize a feeler solenoid operable in the feeler circuit; slide locking pins on the magazine, each spring pressed to engage a locking recess in a cradle slide; a pin shaft parallel to and slidable with the color indication shaft from the color indication mechanism and turnable by the feeler solenoid, said shaft including hands each above a finger on the color indication shaft to disengage each locking pin from its slide locking recess, said hands and the locking pins forming contact poles of a multiple pole selective transfer switch in a transfer electric circuit through a transfer solenoid; said transfer solenoid and means between the transfer hammer dog and the color indication shaft to turn the color indication shaft and cause the appropriate finger to depress the nose of a slide and to discharge a bobbin from its cradle in the magazine into the giveways and at the same time to allow the slide locking pin to relock the slide; and a transfer circuit timing switch to close and open the transfer circuit at a predetermined time in a period of two picks and to start the dog setting means in operation.
